O. SCHELLER ET AL

KEY CONNECTION FOR THE WIRELESS TRANSMISSION OF MESSAGES

Filed Aug. 31, 1921

FIG. 1.

FIG. 2.

INVENTOR:

OTTO SCHELLER,
ROBERT HERZOG,

BY *Alvin Koo*

ATTORNEYS.

UNITED STATES PATENT OFFICE.

OTTO SCHELLER, OF BERLIN-LICHTERFELDE-WEST, AND ROBERT HERZOG, OF BERLIN, GERMANY, ASSIGNORS TO C. LORENZ AKTIENGESELLSCHAFT, OF LORENZWEG, BERLIN-TEMPELHOF, GERMANY.

KEY CONNECTION FOR THE WIRELESS TRANSMISSION OF MESSAGES.

Application filed August 31, 1921. Serial No. 437,281.

(GRANTED UNDER THE PROVISIONS OF THE ACT OF MARCH 3, 1921, 41 STAT. L., 1313.)

To all whom it may concern:

Be it known that we, OTTO SCHELLER, residing at Berlin-Lichterfelde-West, Germany, and ROBERT HERZOG, residing at Berlin, Germany, citizens of the German Republic, have invented certain new and useful Improvements in Key Connections for the Wireless Transmission of Messages (for which we have filed applications in Germany 10 on November 9, 1918, Patent No. 318,845, and July 4, 1919), of which the following is a specification.

This invention relates to a key connection which permits the load of a generator to be 15 maintained steady. The arrangement is specially advantageous in cases where a uniform withdrawal of energy from a generator is considered important for instance with arc light generators and high frequency machines. With arc light generators fluctuations of current is detrimental due to the 20 fact that the unequal load causes variations in the number of revolutions of a generator and consequently alterations in the syntony.

25 The invention consists in employing a capacity adapted to be inserted in parallel connection with the generator, and by means of said capacity the generator remains uniformly loaded. A key is also provided and 30 where the key is depressed the high frequency current from the generator flows into the antenna. When the key is open the energy taken up by the antenna is conducted through the loading condenser.

35 In the path or branch of circuit supplying energy from the generator to the antenna a choke coil is inserted which during the transmission of signals is bridged by means of said key, so that where the key is depressed the generator current can flow into 40 the antenna and when the key is open the current is prevented from flowing into the antenna by the choke coil.

In order that the invention may be clearly 45 understood, we shall proceed to describe the same with reference to the two forms of con-

struction which are diagrammatically shown by way of example in Figures 1 and 2 of the accompanying drawing.

The connection can be carried out as 50 shown on Fig. 1 of the drawing, in which case the high frequency energy of the generator *g* is conducted on the one hand across the loading condenser *c*, the key *t*, the blocking condenser *b* and back to the generator. 55 On the other hand, the high frequency energy is conducted through antenna *A*, coils *s*, key *t*, and blocking condenser *b*. When the key *t* is open, as shown on Figure 1, the generator is loaded from the condenser *c*. 60 When the key is depressed the energy flows into the antenna. The invention can be applied also to a direct connection, differing from the connection shown on Figure 1, in which the generator is situated in the antenna, so that the separate intermediary circuit is suppressed. This connection is shown 65 on Figure 2 in which the same letters of reference indicate the same parts as on Figure 1.

We claim:—

A wireless signal transmission apparatus comprising an antenna, a high frequency generator connected therewith, a condenser adapted to be connected in parallel with the 70 generator, a choke coil normally in series with the generator and antenna, and a key with connections therefor whereby with the key closed the choke coil will be brought into shunt relation to the antenna generator circuit and with the key open the condenser will be connected in parallel to the generator. 75

In testimony whereof we have signed this 80 specification in the presence of two witnesses.

OTTO SCHELLER.
ROBERT HERZOG.
